EDIBLE CONTAINER

Harold W. Corley, Albuquerque, N. Mex.

Application November 21, 1952, Serial No. 22,399

Term of patent 14 years

(Cl. D8—2)

To all whom it may concern:

Be it known that I, Harold W. Corley, a citizen of the United States of America, residing at city of Albuquerque, county of Bernalillo, and State of New Mexico, have invented a new, original, and ornamental Design for an Edible Container, of which the following is a specification, reference being had to the accompanying drawing, forming part thereof.

Figure 1 is a perspective view of an edible container embodying my new design;

Figure 2 is a bottom plan view thereof; and

Figure 3 is a side elevation of the same.

The essential features of my design reside in the portions shown in solid lines on the drawing.

The illustration of a bear is present on the undisclosed sides of the container.

I claim:

The ornamental design for an edible container, as shown and described.

HAROLD W. CORLEY.
